WINDOW VENTILATOR

John O. Smith, Cleveland, Ohio

Application November 18, 1932, Serial No. 643,199

8 Claims. (Cl. 98—99)

This invention relates to window ventilators adapted to be inserted between a sliding sash and the window sill or lintel and designed to permit passage of air into the interior of a room while intercepting direct drafts.

The device of the present invention has for an object to provide a ventilator which is collapsible, and which occupies very little space when collapsed so that it can be conveniently kept on a window ledge or in a bureau drawer when not in use.

A further object is to provide a ventilator which will effectually exclude snow and rain when driven against the ventilator by a heavy wind.

Further objects are to provide a ventilator which is of attractive appearance, which can be manufactured at a small cost and which is easy to apply to or remove from a window.

With the above and other objects in view, the invention may be said to comprise the device as illustrated in the accompanying drawing hereinafter described and particularly set forth in the appended claims, together with such variations and modifications thereof as will be apparent to one skilled in the art to which the invention appertains.

Reference should be had to the accompanying drawing forming a part of this specification, in which:

Figure 1 is a perspective view showing the ventilator of the present invention placed in a window;

Fig. 2 is a side elevation of the ventilator extended;

Fig. 3 is a side elevation of the ventilator collapsed;

Fig. 4 is a sectional view showing the ventilator on the section line indicated at 4—4 of Fig. 2, and also showing the attachment of the ventilator to a window frame;

Fig. 5 is a fragmentary side elevation showing attachment of two ventilator units end to end.

The ventilator of the present invention, as illustrated in the accompanying drawing, consists of inner and outer accordion plaited walls composed of a suitable, flexible material such as a suitably stiffened waterproof fabric, waterproof paper, or other similar material. In forming the ventilator, two strips of the accordion plaited material are laid one upon the other and secured together at the ends and also preferably along the abutting tips of reentrant plaits.

As herein shown the ventilator is composed of two identical plaited strips 1, the strip forming the outer wall having a row of holes 2 along the

lower portion thereof, the strip forming the inner wall having a row of holes 3 along the upper portion. The abutting reentrant plaits are secured together by suitable means such as staples 4, so that the ventilator is composed of a row of joined collapsible tubes 5 which are disposed side by side throughout the length of the ventilator strip. The end portions 6 of the strips 1 are secured together face to face by means of tubular rivets 7 and a laterally projecting tab 8 is secured to the end portion 6 at each end. This tab may be formed of fabric, paper or sheet metal, and if formed of material other than sheet metal preferably has a facing 9 of sheet metal on the outwardly projecting portion thereof as shown in Fig. 4. This tab may be secured in place by one of the metal rivets 7 at each end of the ventilator. The laterally projecting portion of each tab 8 is provided with a keyhole slot 10 adapted to engage over the head 11 of a suitable fastening member such as a screw 12 secured in the jamb of the window frame.

The ventilator of the present invention may be made of any desired length and has considerable range of adjustability to enable it to fit the particular window to which it is to be applied. However, for windows of larger dimensions, two or more ventilator units may be secured together by lapping end portions 6 of the units and securing them together by means of clips 13 extending through the eyelets provided by the tubular rivets 7.

As shown in Fig. 4 of the drawing, the tabs 8 are preferably so engaged with the fastening members 12 that the projecting portions 6 to which the tab is secured is held snugly against the inner face of the sash groove.

When a ventilator is placed in a window beneath a sash the lower edge thereof engages the sill of a window and the upper edge thereof is engaged by the bottom of the sash, the sill closing the lower ends of the tubes 5 and the sash closing the upper ends thereof. Air, however, is permitted to enter the tubes through the holes 2, one in each of the tubes, and enters the room through the holes 3 in the inner wall, which are positioned sufficiently above the holes 2 to prevent entry of rain or snow into a room even though the rain or snow be driven against the ventilator by heavy winds.

In order to easily adjust the ventilator beneath the window sash, one or more intermediate tabs 15 are provided between the ends of the ventilator, these tabs being secured to one of the outwardly projecting plaits of the inner wall thereof.

5 In order to securely hold the ventilator beneath a window sash throughout its length, a number of sash engaging clips 16 are secured to the upper edges of the plaited walls, and these clips are provided with upwardly projecting prongs 17 which engage the bottom of the window sash and firmly hold the ventilator against displacement.

10 It will be apparent that the present invention provides a very simple, inexpensive and convenient ventilator which is a convenient article for tourists since it can be collapsed to a size small enough to permit it to be carried in a coat pocket and may be fitted in windows of various widths.

15 It will also be apparent that very few sizes need be manufactured, by reason of the adjustability and the ease with which units may be joined end to end.

20 Furthermore, it is to be understood that the particular form of product shown and described, and the particular procedure set forth, are presented for purposes of explanation and illustration and that various modifications of said product and procedure can be made without departing 25 from my invention as defined in the appended claims.

What I claim is:

30 1. An extensible collapsible ventilator adapted to be interposed between an end of a sliding window sash and the window frame and comprising two flexible accordion plaited strips secured together at their ends, the plait extending transversely of the strips and the strips being disposed with the reentrant plaits of one opposite reentrant plait of the other whereby vertical open ended passages are provided between the walls which are closed at their ends by the sash and frame when the ventilator is in place between the sash and frame, said inner and outer walls having openings at different heights which with said vertical passages provide for flow of air in a tortuous path through the ventilator.

45 2. A window ventilator comprising an extensible collapsible strip adapted to be extended and interposed transversely across a window opening between a sliding window sash and its frame and having means at the ends thereof for attachment to opposite sides of the window frame, said strip being composed of a row of collapsible tubes disposed transversely of the strip and in vertical position in a window opening, said tubes being joined one to another throughout their length, each tube having openings at different heights to the inner and outer sides of the ventilator.

50 3. An adjustable window ventilator adapted to be extended transversely across a window opening and interposed between a window sash and its frame and having extensible collapsible inner and outer walls in the form of accordion plaited strips, said strips having their reentrant plaits joined edge to edge to form a series of collapsible tubes which are disposed vertically in the window opening, said inner and outer walls having openings to each tube.

55 4. An adjustable window ventilator adapted to be extended transversely across a window opening and interposed between a window sash and its

frame and having extensible collapsible inner and outer walls in the form of accordion plaited strips, said strips having their reentrant plaits joined edge to edge to form a series of collapsible tubes which are disposed vertically in the window opening, said inner and outer walls having openings to each tube, the inner and outer openings being at different heights, the strips having end portions joined face to face to provide extensions adapted to project into the sash groove of the window frame, and laterally projecting tabs secured to said end portions for attachment to the window frame. 5

5. An adjustable window ventilator adapted to be interposed between a window sash and its frame and having extensible collapsible inner and outer walls in the form of accordion plaited strips, said strips having their reentrant plaits joined edge to edge to form a series of collapsible tubes, said inner and outer walls having openings to each tube, the inner and outer openings being at different heights, and sash engaging clips attached to the upper edges of said inner and outer walls. 20

6. An adjustable window ventilator adapted to be interposed between a window sash and its frame and having extensible collapsible inner and outer walls in the form of accordion plaited strips, said strips having their reentrant plaits joined edge to edge to form a series of collapsible tubes, 30 said inner and outer walls having openings to each tube, the inner and outer openings being at different heights, and sash engaging clips attached to the upper edges of said inner and outer walls, said clips having upwardly projecting prongs for engagement with the window sash.

7. An adjustable window ventilator adapted to be interposed between a window sash and its frame and having extensible collapsible inner and outer walls in the form of accordion plaited strips, 40 said strips having their reentrant plaits joined edge to edge to form a series of collapsible tubes, said inner and outer walls having openings to each tube, the inner and outer openings being at different heights, the strips having end portions joined face to face by tubular rivets which provide eyelets for attaching clips whereby ventilator units may be joined end to end. 45

8. An adjustable window ventilator adapted to be extended transversely across a window opening and interposed between a window sash and its frame and having extensible collapsible inner and outer walls in the form of accordion plaited strips, 50 said strips having their reentrant plaits joined edge to edge to form a series of collapsible tubes which are disposed vertically in the window opening, said inner and outer walls having openings to each tube, the inner and outer openings being at different heights, the strips having end portions joined face to face to provide extensions adapted to project into the sash groove of the window frame, and laterally projecting tabs secured to said end portions for attachment to the window frame, said walls being formed of waterproof paper and said tabs being formed of sheet metal. 55

JOHN O. SMITH.
